INTEGRAL BARREL LOCK AND EXTRACTOR

Ernest P. Simmons, Kansas City, Kans., assignor to Olin Mathieson Chemical Corporation, a corporation of Virginia

Application December 2, 1954, Serial No. 472,633

2 Claims. (Cl. 42—75)

This invention relates to new and useful improvements in automatic shotguns, and has particular reference to a safety device preventing the removal of the barrel of an automatic shotgun of the split-chamber type when there is a shell in firing position in the chamber.

In automatic shotguns of the split-chamber type, the chamber, instead of being formed in the breech end of the barrel itself, is formed in a separate chamber member carried by the receiver. This chamber member, when the gun is in firing position, is locked into the receiver by means entirely independent from the connection of the barrel into the receiver. Thus when in the ordinary dismantling of the gun for storage the barrel is detached from the receiver, it is entirely possible that a shell may be left in the chamber in position for firing. This is of course extremely dangerous, in that the gun may subsequently be accidentally discharged by jarring or by careless handling during storage, or when next reassembling the gun. The prime object of this invention is the provision of a very simple and economical means which absolutely prevents this occurrence, and which requires that the shell in the chamber be removed, or at least that the bolt be moved to a non-firing position, before the barrel can be detached from the receiver.

This object is accomplished in general by the provision of a locking member attached to the bolt of the gun and projecting forwardly sufficiently far, when the bolt is closed for firing, to engage in a notch formed in the breech end of the barrel. The barrel is thus locked against rotation, and thereby against removal from the receiver, since this removal requires at least a partial rotation of the barrel. When the bolt is retracted manually, the locking member is withdrawn from the barrel notch and the barrel may be removed, but at the same time the usual extractor, which is also carried by the bolt, extracts the shell from the chamber, and the shell is ejected from the gun.

It has been found that the locking member may advantageously be formed as an extension of the extractor itself, and when so formed has an additional desirable effect on the ejection action of the gun. It decreases the force and distance that the shell casings are ejected from the gun, causing them to fall close to the gunner. This is advantageous particularly in shooting matches where the gunners stand abreast, and shells ejected from one shooter's gun often strike adjacent shooters.

Other objects are simplicity and economy of construction, efficiency and dependability of operation, and adaptability to be incorporated in pre-existing guns with a minimum amount of alteration.

With these objects in view, as well as other objects which will appear in course of the specification, reference will be had to the drawing, wherein:

Fig. 1 is a longitudinal mid-sectional view of the receiver and adjacent portions of an automatic shotgun embodying the present invention, with parts left in elevation.

Fig. 2 is a fragmentary view similar to Fig. 1, with additional parts left in elevation.

2

Fig. 3 is a slightly irregular sectional view taken on line III—III of Fig. 1, with parts left in elevation.

Fig. 4 is a sectional view taken on line IV—IV of Fig. 1.

5 Fig. 5 is a sectional view taken on line V—V of Fig. 1, with parts left in elevation.

Fig. 6 is a sectional view taken on line VI—VI of Fig. 2, with parts left in elevation.

Like reference numerals apply to similar parts throughout the several views, and the numeral 2 applies to the receiver portion of an automatic shotgun of the split-chamber type, said receiver being hollow and elongated longitudinally of the gun and having right and left side walls 4 and 6, top wall 8, front wall 10, rear wall 12, and being open at the bottom. The rearward portion of the bottom opening is closed by a trigger frame 14 held in the receiver by an assembly pin 16. The forward portion of the bottom opening is occupied by a shell carrier 18 carried movably by frame 14. Said shell carrier forms no part of the present invention, but its function will be described generally below.

The gun barrel 20 is threaded into a bore 22 formed through the front wall 10 of the receiver, and communicates with the interior of the receiver. The threads of this connection may be standard, but more commonly are of the "bayonet" type, only the opposite quadrants of the barrel and bore 22 being threaded, as indicated in Fig. 6. In assembling, the barrel threads may be inserted axially to their full depth into the receiver bore 22, and the barrel then rotated 90 deg. to bring the threads into engagement. A magazine tube 24 is disposed beneath and parallel to the barrel, and is also threaded at its rearward end into front wall 10 of the receiver in communicating relation with the interior of said receiver. Shells 26 carried in said magazine tube are urged rearwardly by a spring, not shown, carried in the forward end of said tube. The barrel is normally prevented from rotating by a connection thereof, not shown, to tube 24, such as a radial arm fixed to the barrel and detachably connected to tube 24.

Carried for longitudinal sliding movement in the rearward end portion of the barrel is a tubular shell chamber 28 adapted to receive a shell 26 therein as best shown in Figs. 1 and 3. Said chamber is provided at its rearward end with an internal shoulder 30 against which the rim 32 of the shell abuts, and an external shoulder 34 which normally abuts the rearward end of the barrel. The chamber is provided with a rearward extension 36 having the form generally of a downwardly opening semi-cylinder. The rearward end of said extension terminates in spaced relation to a forwardly facing shoulder 38 formed internally in receiver 2. As best shown in Figs. 1 and 3, a pin 40 is carried slidably in a bore 42 formed in the wall of said extension, and is urged rearwardly against shoulder 38 by a compression spring 44 carried in said bore. The chamber shoulder 34 is thus urged forwardly at all times toward engagement with the rearward end of the barrel.

The bolt 46, when the gun is closed, is disposed within chamber extension 36, the forward end thereof abutting the rearward end of the shell in the chamber, as shown in Figs. 1 and 3. Adjacent its rearward end, said bolt is provided with an upwardly projecting lug 48, which projects into a slot 50 formed in the upper wall of chamber extension 36, whereby to lock the bolt against rearward movement relative to the extension. The bolt is positively secured against any further forward movement in the receiver by the engagement of a depending lug 52 (Fig. 1) integral with the bolt against the inner face of the front wall 10 of the receiver. The mating surfaces of lug 48 and slot 50 are inclined whereby to provide a cam action forcing the bolt firmly forward against the

shell when the bolt is moved upwardly. The bolt carries a firing pin 54 therein. Said firing pin is urged rearwardly in said bolt against a stop pin 56 by a spring 58, so that the forward end thereof is disposed rearwardly of the forward end of the bolt, and the rearward end thereof projects rearwardly from the back end of the bolt. A hammer 60 pivoted in trigger frame 14 at 62 is urged pivotally forwardly by spring 64 to strike the rearward end of the firing pin to drive it forwardly to detonate the shell in the chamber in the usual manner. Said hammer is normally retained in its cocked position by the engagement in a notch 66 thereof of the toe 68 of a trigger 70 pivoted in frame 14 at 72. When the trigger is pulled rearwardly against the pressure of trigger spring 94, the toe thereof is disengaged from the hammer notch 66, and the hammer functions as described.

The bolt also carries an ejector pin 76 for longitudinal movement in approximately parallel relation to but spaced transversely apart from the firing pin. The ejector pin is urged rearwardly in the bolt by a spring 78 carried in the bolt, whereby a shoulder 88 (Fig. 3) thereof engages a matching shoulder of the bolt. In this position the forward end of the ejector pin is retracted within the bolt, and the rearward end projects outwardly from the rearward end of the bolt.

The bolt also carries an extractor 82 comprising a generally L-shaped lever having one arm 84 pivoted in the bolt on a vertical pivot pin 86 and projecting outwardly from said bolt transversely of the gun, as best shown in Fig. 3, and a right angled arm 88 extending forwardly along the side of the bolt to a point ahead of the forward end of the bolt. The extractor arm 88 is urged resiliently toward the bolt by a spring 90 carried in the bolt. Arm 88 extends forwardly through a notch 92 formed through the rim of the chamber 28 between shoulders 30 and 34 thereof. Said arm is provided at its forward end with a tooth 94 which engages the forward edge of the rim 32 of the shell in the chamber (Fig. 3). Extractor arm 88 is provided with a forward extension 96 which, when the bolt is closed, projects into a notch 98 formed in the external surface of the rearward end of barrel 20. The function of the extractor and extractor extension will be fully described below.

The bolt is supported in the receiver by a horizontal pin 100 extending transversely of the gun and passing through a pair of matching slots 102 formed in a pair of side walls 104 and 106 which are integral with and depend from the bolt. The forward end portions of said slots, in which pin 100 is disposed when the bolt is closed, are substantially horizontal. The rearward portions of said slots are inclined upwardly and rearwardly, for a purpose which will appear. Pin 100 extends outwardly from the sides of the bolt, and the ends thereof are mounted in slides 108 and 110. Said slides are mounted for forward and rearward sliding movement respectively in grooves 112 and 114 formed in the inner surfaces of receiver walls 4 and 6 (Fig. 4). The right slide 108 is provided with a thumb-piece 116 which projects outwardly through a slot 118 formed in receiver wall 4, whereby said slide may be operated manually. Said slot is upwardly enlarged as at 120 to form an opening through which shells may be ejected.

A link 122 is pivoted on pin 100 between bolt side walls 104 and 106, and extends rearwardly through the receiver. Hammer 60 operates through a longitudinal slot 124 formed in said link. At its rearward end, said link is pivoted at 126 to an inertia rod 128 which is carried for longitudinal sliding movement in a tubular extension 130 of the receiver, said extension being disposed in the stock 132 of the gun. A recoil spring, not shown, is disposed in tube 130 behind rod 128, and urges said rod forwardly.

The general operation of the gun is as follows: When the gun is fired as previously described, the chamber

28, extension 36, and bolt 46 first recoils rearwardly as a unit against the pressure of spring loaded pin 40, since the bolt is locked in the chamber extension. The bolt motion is also transmitted through pin 100 and link 122 to inertia rod 128, imparting substantial momentum thereto. The rearward movement of the chamber is arrested after a short travel by the engagement of the rearward end of extension 36 with receiver shoulder 38, but inertia rod 128 continues rearwardly by its momentum, carrying pin 100 rearwardly in bolt slots 102. When pin 100 engages the inclined rearward portions of said slots, it cams the rearward end of the bolt downwardly, lowering bolt lug 48 from the slot 50 of the chamber extension. The momentum of inertia rod 128 then carries the bolt rearwardly independently of the chamber. During this movement, the extractor tooth 94, which is in engagement with the rim 32 of the expended shell in the chamber, pulls the shell out of the chamber. As the bolt approaches the rearward end of the receiver, the rearward end of ejector pin 76 engages and is arrested by rear wall 12 of the receiver, thus forcing said ejector forwardly with respect to the bolt, against the pressure of ejector spring 78, as the bolt continues its rearward movement. The forward end of the ejector pin is thus projected through the forward end of the bolt into engagement with the shell, thereby pivoting it around extractor tooth 94 and throwing it outwardly through ejection opening 120 of the receiver.

The bolt is then ready to start its forward movement under the urging of the recoil spring. During its rearward movement a new shell 26 was ejected from the magazine tube 24 by the magazine spring onto shell carrier 18. As the bolt starts its forward movement, it engages a suitable mechanism (not shown) carried by trigger frame 14 and operable to flip shell carrier 18 upwardly to move the shell carried thereby into the path of the bolt. The bolt then continues forwardly to its locked position, pushing the shell into chamber 28.

While the above description of operation is somewhat incomplete and sketchy, it is believed sufficient to illustrate the operation of the barrel locking mechanism. It is apparent that when the bolt is closed and locked, as shown in Figs. 1 and 3, extension 96 of extractor 82 is engaged in notch 98 of the barrel, thereby locking the barrel against rotation and preventing the removal thereof from the receiver. To remove the barrel, the operator must first pull thumb-piece 116 rearwardly, thereby moving pin 100 and slides 108 and 110 rearwardly, sufficiently far to cause pin 100 to cam the bolt downwardly to unlock lug 48 thereof from chamber extension slot 50 as previously described, and still further to move the bolt rearwardly with respect to the chamber. The bolt movement pulls the extractor extension rearwardly from barrel notch 98, and the barrel may then be rotated and removed.

While only a short bolt movement is required to free the barrel, it is contemplated that the operator, if he attempts to remove the barrel and finds it locked, will be reminded that there may be a live shell in the chamber and will hence pull the bolt back not only far enough to free the barrel, but all the way back to eject the shell. However, if he does pull the bolt back only far enough to free the barrel and not far enough to eject the shell, the gun will still remain safe. When the barrel is removed, the chamber is urged forwardly by pin 40 and spring 44 to such a point that bolt lug 48 cannot enter slot 50 of the chamber extension, but strikes the inner wall of said chamber extension. If thumb-piece 116 is then released, pin 100 will be trapped in the rearward inclined portions of bolt slots 102, and will hold link 122 in a rearward position. If the trigger is then pulled, hammer 60 will strike link 122 at the forward end of slot 124, at point 134 (Fig. 1), and be prevented thereby from striking the firing pin.

It will be apparent also that the extension 96 of the

extractor will affect the normal ejection action of the gun, since the shell as it is ejected strikes against the extension. Its effect is to substantially reduce the distance the shell is thrown. This is considered an advantage particularly in match shooting, wherein the gunners often stand abreast on a firing line and are quite often struck by shells ejected from the guns of those adjacent in line.

While I have shown and described a specific embodiment of my invention, it will be readily apparent that many minor changes of structure and operation could be made without departing from the spirit of the invention as defined by the scope of the appended claims.

What I claim as new and desire to protect by Letters Patent is:

1. In an automatic shotgun, a receiver, a barrel secured at its rearward end in said receiver by a rotatably detachable connection, a tubular chamber disposed slidably in the rearward portion of the barrel and extending into the receiver, said chamber being operable to receive a shotshell and having an internal shoulder for engaging the rim of the shell, said chamber shoulder being formed with a first notch, a bolt slidably disposed within the receiver, means operative to lock the bolt in a battery position in the extension of said chamber whereby the

forward end of the bolt abuts the head of said shell, and a locking member pivotally mounted to the bolt and received by said first notch and extending forwardly to engage a second notch formed in the rear end of the barrel effective to lock the barrel to the chamber.

2. The structure set forth in claim 1 wherein the bolt carries a pivotally mounted extractor comprising an arm secured to the bolt and extending forwardly therefrom past the edge of said shell rim and being provided with a tooth operable to engage said shell rim to extract the shell from the chamber when the bolt is moved away from its battery position, said locking member comprising a forward extension of the extractor arm.
